(57) CLAIM

What is claimed is the ornamental design for an interlocking tile for ice surfaces, as shown and described.

DESCRIPTION

FIG. 1 is a right elevational perspective view of the interlocking tile for ice surfaces in accordance with our invention;

FIG. 2 is a top view thereof;

FIG. 3 is a bottom view thereof;

FIG. 4 is a front view thereof;

FIG. 5 is a back view thereof;

FIG. 6 is a left side view thereof; and,

FIG. 7 is a right side view thereof.
